GAS FUELED IGNITER

Ross H. Forney, Dallas, Tex.

Application November 18, 1949, Serial No. 128,109

2 Claims. (Cl. 158—115)

1

This invention relates to new and useful improvements in means for igniting pilot burners.

A particular object of the invention is to provide a new and improved means for igniting the pilot burners for large furnaces in which the pilot burners maintain the ignition of the main furnace burners.

An important object of the invention is to provide improved means for igniting pilot burners wherein a mixture of air and a combustible gas or vapor is fed to the pilot burner and electrically ignited by a spark, resulting in ignition of the pilot burner.

A further object of the invention is to provide improved means for igniting a pilot burner in which air and a combustible gas under pressure are fed to an explosion chamber and there subjected to an electric spark, the flame propagated from the resultant explosion being conducted to the ignition point for said pilot burner.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a view in perspective taken from the outer side of the furnace wall and illustrating a pilot burner ignitor constructed in accordance with this invention.

Fig. 2 is a longitudinal, vertical view of the pilot burner and the main furnace burner, the view being partially broken away.

Fig. 3 is an enlarged sectional view of the explosion chamber, and

Fig. 4 is a schematic wiring diagram of the electrical portion of the invention.

In the drawings, the numeral 10 designates the wall of a furnace firebox, and the numeral 11, the usual secondary or protective wall carrying the burner fittings. A main burner tube assembly 12 is positioned in the wall 11 and extends into the furnace firebox through the wall 10. This structure is usual and customary and does not form a portion of the present invention.

A pilot burner structure, designated generally by the numeral 13, is also mounted in the wall 11 and extends into the furnace above the burner structure 12 for the purpose of providing a pilot flame for igniting or maintaining the ignition of the main burner. The pilot burner structure includes a central gas or combustible fuel conductor 14 extending axially of an outer conductor

15, the two conductors extending through a mounting tube 16 positioned in the wall 11. As shown in Fig. 2, the conductor 15 is formed with a plurality of enlarged sections 16 having radial ports 17, and a muffle or shroud 18 is carried upon the inner or furnace end of said conductor structure 15. The inner conductor 14 extends throughout the length of the conductor 15 terminating at 19 a short distance within the muffle 18. A plurality of air inlet ports 20 are cut in the closed end of the muffle 18 in the usual manner.

A mounting plate 21 is positioned outwardly of the wall 11, adjacent the outer end of the mounting tube 16. The plate 21 carries the ignitor controls to be described hereinafter and may be supported in any suitable fashion. At the outer end of the conductors 14 and 15, an explosion or ignition fitting 22 is provided. The fitting 22 is elongate in shape and is provided with a stepped internal axial passage 23 extending from the forward end thereof to a point adjacent the rearward portion of said fitting. The rearmost portion 24 of the passage 23 is relatively small in diameter and carries screw-threads 25 receiving the screw-threaded rearward end 26 of the pipe 14. A lateral branch passage 27 communicates with the portion 24 and is screw-threaded to receive a conductor 28 extending laterally from the rearward portion of the fitting 22.

Forwardly of the screw-threads 25, the passage 23 is enlarged to form a counterbore 29 and provide an annular space 30 about the rearward portion of the pipe 14. A second lateral passage 31 enters the fitting 22 forwardly of the space 30 and communicates with a second counterbore or enlargement 32 of the passage 23. The passage 31 is screw-threaded to receive a conductor 33 extending laterally from the fitting 22, and the second counterbore 32 is also provided with internal screw-threads receiving the screw-threaded rearward end 34 of the pipe 15. With this arrangement, communication is had through the pipe 33 with the interior of the pipe 15, while communication is had through the pipe 28 with the interior of the pipe 14.

Fuel gas for the pilot burner is normally supplied through the conductor 28, and for this purpose, a gas supply pipe 35 forms a part of the apparatus. The pipe 35 is disposed laterally of the pilot arrangement and is connected through a T 36 to an elongate manifold 37 extending horizontally between the shield 11 and the mounting plate 21. Of course, the manifold may be extended to any desirable length so as to supply gas to the pilot burners for additional main

furnace burners associated with the burner described. A suitable pressure gauge 38 is connected to the opposite branch of the T 36 for indicating the pressure of the fuel gas supply.

Substantially in vertical alinement with the tube 16, the manifold 37 carries a T 39 into which a branch pipe 40 is connected. A cutoff valve 41 is located in the pipe 40 and also a solenoid valve 42. Outwardly of the valve 42, a union 43 is positioned in the pipe 40, the latter terminating in the downwardly directed elbow 44 to which is connected a vertical conductor 45. A T 46 is connected to the lower end of the conductor 45, and a pipe 47 extends downwardly from the T, being connected through a union 48 with the upper end of the pipe 28. Thus, fuel gas may flow from the pipe 35 through the various pipe and connections described to the pipe 28, and thence to the pipe or conductor 14.

Air under pressure for combustion purposes is similarly furnished through a supply pipe 49 disposed laterally of the pilot structure and being connected through a T 50 into an air manifold 51 extending parallel to and below the manifold 37. A suitable pressure gauge 51' is connected to the T 50. At an intermediate point, the manifold 51 is provided with a T 52 carrying a lateral conductor 53 having therein a suitable cutoff valve 54 and a union 55. An upwardly directed elbow 56 is mounted upon the outer end of the pipe 53 and carries an upwardly extending conductor 57 having an elbow 58 upon the upper end thereof to which is connected a pipe 59 extending parallel to the manifold 51 toward the right hand side of the structure as viewed in Fig. 1. The pipe 59 is connected into an enlarged T 60 in vertical alinement with the pipe 33, and a conductor 61 extends downwardly from said T to the upper end of the pipe 33, there being incorporated into the pipe 61 a union 62 and a T 63. A pipe or conductor 64 leads from the lateral branch of the T 46 to the remaining branch of the T 60, and in this manner fuel gas as well as air under pressure may be communicated and conducted to the pipe 61 and the T 63.

Suitable electrical control apparatus is carried upon the supporting plate 21, the wiring diagram for the equipment being schematically illustrated in Fig. 4. A main electrical power supply cable 65 is provided, and supplies electrical power through a junction box 66 to a solenoid circuit 67 and an ignitor circuit 68. The solenoid circuit extends through a tumbler switch 69 to a pilot light 70 and a solenoid armature 71 connected in parallel across said switch. Thus, when the switch 69 is closed, the pilot light 70 is ignited and the solenoid armature 71 is actuated to open the solenoid valve 42.

The ignitor circuit is connected in series through a push button, momentary contact switch 72 and the primary coil 73 of a high voltage output transformer 74. The secondary coil 75 of the transformer 74 is connected between ground and a spark plug 76 carried in the lateral branch of the pipe T 63. Thus, upon closing of the switch 72, a momentary high voltage is applied to the spark plug 76 which is thereby caused to produce an electrical spark within the interior of the pipe T 63.

In the operation of the device, the valves 41 and 54 are opened to admit fuel gas and air under pressure, and the switch 69 is closed to actuate and open the solenoid valve 42. Fuel gas now flows through the pipe 28 to the pipe 14 and thence to the furnace end 19 of said pipe. Simul-

taneously, gas flows through the pipe 64 into the pipe T 63, and through the pipe 33 into the interior of the pipe 15. The air under pressure flows to the pipe 59 and through the T 60 to the T 63 and also into the interior of the conductor 15. An explosive mixture of air and fuel gas is thus present within the T 63, and shortly after opening of the valves, throughout the interior of the pipe 15 surrounding the pipe 14.

The momentary contact switch or push button 72 is now closed which causes the spark plug 76 to function and produce a spark within the T 63. The spark ignites the air and gas mixture, resulting in a rapid combustion or explosion which is propagated throughout the length of the pipe 15 and ignites the fuel gas issuing from the furnace extremity 19 of the pipe 14. The violence of the explosion is somewhat mitigated by the enlarged portions 16 and the ports 17 which relieve the accumulated explosion pressure and provide for a diminishing of any destructive forces resulting from the explosion. The propagation of the flame is not interrupted by these enlarged portions or ports, however, and the flame is conducted to the end 19 of the conductor 14 to ignite the fuel gas flowing therethrough and result in lighting of the pilot burner. Of course, the pilot flame issues from the end of the muffle 18 and functions to ignite the main burner 12 when so desired, or to maintain the ignition of said burner.

Normally, the supply of air is cut off as soon as the pilot flame is brought into existence, and although some gas may continue to flow through the pipe 64 and the pipe 15, it merely burns within the muffle 18 and is consumed in the pilot flame.

In the event the pilot flame is not ignited upon the first effort, the described operation may be continued any desirable number of times until successful ignition is obtained. In practice, however, it has been found that the present device ignites the pilot flame upon the first attempt in nearly every case, and the repeated ignition efforts are not required.

When it is desired to extinguish the pilot burner, the switch 69 is easily and quickly opened, resulting in closing of the solenoid valve 42 and the substantially instantaneous shutting off of the fuel gas flowing to the pilot burner. This action is much faster, and may be accomplished much quicker than manually closing the valve 41. Of course, the latter valve may be closed after the pilot flame is extinguished in order to provide for a double shut-off of the fuel gas with the enhanced safety resulting therefrom. The pilot light 70 is illuminated at all times the solenoid valve 42 is open and serves to notify the operator of such fact.

It is to be noted that the spark plug 76, and indeed the entire electrical system, are located outside of the furnace and are not subjected to furnace temperatures. The various portions of the electrical equipment will not stand continuous high temperatures, and this provision greatly lengthens the operating life of the equipment by situating it at the outer end of the pilot burner rather than at the inner end thereof. The provision of all of the control devices without the furnace also causes this invention to be particularly applicable to the new types of furnaces in which an entire boiler setting is carried under an appreciable pressure. It is almost physically impossible to employ the old type of lighting by means of a hand torch in this new type of furnace because the outward blast of air through an open port through which the hand torch must

be inserted would immediately extinguish the torch and prevent the lighting operation being successfully concluded. This is not true with the present invention which contemplates a permanent installation which may be made pressure tight, and in which all manipulations are carried on at a point remote from the combustion chamber of the furnace.

The entire arrangement is very simple and easy to operate and affords great convenience to the tender of the furnace. Since the equipment is always in position and is operable upon a moment's notice the pilot burner can be very quickly and readily ignited or extinguished. Further, since all but the burner portion of the pilot is situated remote from the combustion chamber of the furnace, the equipment is not subjected to adverse operating conditions and has an indefinite but extremely prolonged operating life.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A pilot burner and ignitor for furnaces including, an elongate tube, an elongate sleeve substantially co-extensive with the tube and surrounding the latter throughout substantially its entire length to form a burner and ignitor assembly adapted to be positioned with one end adjacent the main burner of a furnace, a fitting receiving the opposite end of the assembly remote from the burner end thereof, said fitting having

10
15

a passage communicating with the tube and a passage communicating with the sleeve, means supplying fuel gas to each passage, means supplying air under pressure to the passage communicating with the sleeve, and electrical ignition means communicating with the latter passage adjacent the fitting.

2. A pilot burner and ignitor for furnaces including, an elongate tube, an elongate sleeve substantially co-extensive with the tube and surrounding the latter throughout substantially its entire length to form a burner and ignitor assembly adapted to be positioned with one end adjacent the main burner of a furnace, a fitting receiving the opposite end of the assembly remote from the burner end thereof, the fitting having a passage communicating with the tube and a passage communicating with the sleeve, conductor means supplying fuel gas under pressure to each passage, conductor means supplying air under pressure to the passage communicating with said sleeve, and electrical ignition means in the latter conductor means adjacent said fitting.
